JAMES D. McCALL, OF MC CALL, IDAHO.

RAIL-JOINT.

1,146,634.

Specification of Letters Patent. Patented July 13, 1915.

Application filed April 12, 1915. Serial No. 20,735.

To all whom it may concern:

Be it known that I, JAMES D. McCALL, a citizen of the United States, and a resident of McCall, in the county of Boise and State of Idaho, have invented certain new and useful Improvements in Rail-Joints, of which the following is a specification.

This invention relates to an improvement in rail joints, and more particularly in improved joints of the continuous rail type.

One of the principal objects of my invention is to provide an improved rail joint of the continuous rail type, of such nature that the rails are readily interchangeable and the ends of the rails so fashioned that low joints and spreading rail ends are eliminated.

A further object of my invention is to provide a rail joint of the class described which is extremely simple, and at the same time durable, efficient in operation, and extremely economical of manufacture, by reason of the fact that each end of each rail is machined in exactly the same manner, so that the same machinery may be utilized in finishing both ends of every rail, thus eliminating the requirement of machines of various types for finishing in various manners the ends of the rails, and the employment of extra labor.

A still further object is to provide a rail joint in which the expansion of the various parts will be equalized and the strain imparted to the joints through action of the rolling stock and changes in atmospheric conditions, will be equally distributed to the various elements constituting the joints, so that uneven wear and strain of the joints will be thus minimized.

With these and other objects in view which will become apparent as the description proceeds, the invention resides in the construction, combination, and arrangement of parts hereinafter more fully described and claimed, and illustrated in the accompanying drawings in which like characters of reference indicate like parts throughout the several figures, of which—

Figure 1 represents a view in perspective of a rail joint constructed according to my invention. Fig. 2 represents a top plan view thereof. Fig. 3 represents a view in elevation of one end of one of the members of the joint. Fig. 4 represents a view in perspective of the adjacent rail ends consti-

tuting the joints, separated. Fig. 5 represents a view in section taken transversely on the plane indicated by the line 5—5 of Fig. 2. Fig. 6 represents a view in perspective of the connecting bolt.

In carrying out my invention, I have devised a joint of such nature that both ends of each rail forming the track, are made exactly in the same manner. It will therefore be necessary only to describe the formation of one end of a rail in order to understand the device.

Each rail near its end has its web portion thickened as at 5, the width of the thickened portion being coincident with the width of the ball 6 of the rail, said thickened web portion extending downwardly to the base flange of the rail. At diagonally opposed points of the thickened web portion, the rail end is longitudinally recessed or rabbeted as at 8 and 9 respectively. The floor 10 and wall 11 of each rabbet lie in planes at right angles to each other. Each rabbet is of a width equal to half the thickness of the thickened web portion 5, and of a depth equal to half the height of the rail. Each recess or rabbet 8 or 9 at its inner end terminates in a shoulder 12 having a beveled face 13 directed toward the recess. These beveled surfaces 13 lying on opposite sides of the longitudinal central line of the rail are disposed substantially at right angles to each other. The planes of the beveled surfaces 13 extend toward the end of the rail.

By thus rabbeting the rail ends as described, the diagonally opposed tongues 14 and 15 respectively, are defined on each rail end. These tongues are of the height and width each respectively equal to one half the height and width of the rail at the thickened portion 5. Each of the tongues is beveled at its outer end as at 16, the planes in which the beveled surfaces 16 on opposite sides of the central longitudinal line of the rail lie, being disposed substantially at right angles to each other, and substantially at right angles to the planes in which the beveled surfaces 13 on analogous sides of the rail lie.

Midway the length of the rabbets, the rail end is provided with a preferably rectangular transversely extending opening 17. The opening is situated midway of the top and bottom of the rail, and thus provides a channel in the lower and upper surfaces of

the tongues 14 and 15 respectively. The ends of the base flanges 7 of the rail are cut square as at 18.

In assembling the device, the rail ends are put together in a manner indicated in Fig. 1, in such position that the tongues 14 and 15 of one rail end project into the rabbets 8 and 9 respectively of the adjacent rail ends. When in finally assembled position, the beveled ends 16 of the tongues engage and abut against the beveled surfaces 13 of shoulders 12. At the same time the lower and inner faces of the tongues 14 rest against the floors and inner faces respectively of the rabbets 8, while the upper surfaces and inner surfaces of tongues 16 rest against the analogous surfaces of the rabbets 9. The squarely cut base flange ends also abut against each other in the manner indicated.

The opening 17 is provided for the reception of a rectangular pin or bolt 19. The latter is preferably headed at one end as at 20, and at its opposite end is rounded and screw threaded as at 21. The bolt 19 is not designed to prevent relative lateral shifting movement of the rail ends, since this is prevented by the interlocking engagement of the tongues provided on the adjacent rail ends. However, the bolt is designed to prevent, or at least to limit, the longitudinal movement of the rail ends relatively to each other. By engaging, as it does the channels in the tongues of the rail ends, relative longitudinal shifting movement is effectually prevented.

It will be noted that the tongues provided on each rail end are not connected by any web portion, the rail ends being so machined that the adjacent corner edges of the tongues to all intents and purposes lie against each other, although it will of course be understood that some slight space must necessarily be left between them, in order that the tongues on the two adjacent rail ends may be moved into interlocking position. However, the fit between the tongues is extremely accurate, so that no inconvenience is experienced from this condition.

By having the interlocking faces of the tongues and shoulders beveled, a continuous surface for the passage of the wheels of the rolling stock is provided, no shocks or unevenness incident to the passage of rolling stock over the rail ends of ordinary construction, being experienced. Furthermore, the interlocking engagement between the ends of the tongues and the inner ends of the rabbets or recesses effectually prevents any tendency which the tongues might have for spreading.

By having each end of all the rails thus constructed in the same manner, an economy in the manufacture of the rails will be obtained, for reasons heretofore set out. Fur-

thermore, the strain incident to the contraction and expansion of the parts, due to atmospheric changes, and the strain arising from the passage of rolling stock over the joints, will be equally distributed, so that each of the tongues will bear its proportionate share.

Although I have described the preferred embodiment of my invention, I may desire to make such changes in the construction, combination, and arrangement of parts thereof, as do not depart from the spirit of the invention and the scope of the appended claims.

It will be understood that the method I have provided of connecting rail ends is not limited to that use alone, but may be employed wherever found practical and desirable in construction work.

I claim:—

1. A rail having its web thickened at each end, said thickened web being provided with diagonally exposed longitudinally extending rabbets, each being of a width and depth substantially equal to one-half the width and height of the rail at its ends, a shoulder formed at the inner end of each recess and being provided with a beveled surface, the planes in which the beveled surfaces of the shoulders on opposite sides of the central longitudinal line of the rail lie being disposed substantially at right angles to each other, tongues formed on the rail ends in opposed relation to the rabbets, and being each of a width and thickness substantially equal to one-half the width and height respectively of the rail ends, said tongues at their outer ends being beveled, the planes in which the outer tongue ends on opposite sides of the rail lie being disposed substantially at right angles to each other and at right angles to the planes in which the beveled surfaces of the shoulders on analogous sides of the rail lie, said rail being provided substantially midway between the ends of the rabbets and midway the height of the rail with a laterally extending opening defining channels in the upper and lower surfaces respectively of the opposed tongues, and a bolt adapted to be extended through the registering openings in opposite rail ends when the latter are engaged together, substantially as described.

2. A rail joint comprising a pair of interlocking rail ends, each rail end being provided with a thickened web portion having diagonally opposed longitudinally extending rabbets therein, said rabbets each being of a depth and width substantially equal to one-half the height and thickness respectively of the rail ends, tongues defined at the rail ends in opposed position relatively to the rabbets, each of said tongues being substantially equal in height and width to one-half the height and width respectively

of the rail ends, the outer ends of the tongues of each rail end and the inner ends of the rabbets of the opposite rail end being so formed as to provide an interlocking engagement when the rails are in position, said rail ends being provided with a registering opening for the reception of a bolt.

3. A rail joint comprising a pair of interlocking rail ends, each rail end being provided with diagonally opposed rabbets of a depth and width substantially equal to one-half the height and width respectively of the rail ends, diagonally opposed tongues defined at the rail ends and being each of a height and width substantially equal to one-half the height and width of the rail ends, said rail ends being provided substantially midway the length of the rabbets and midway the height of the rail with a laterally extending opening defining channels in the upper and lower surfaces respectively of the opposed tongues.

4. A rail joint comprising a pair of interlocking rail ends, each rail end being provided with diagonally opposed rabbets of a 25 depth and width substantially equal to one-half the height and width respectively of the rail ends, diagonally opposed tongues defined at the rail ends and being each of a height and width substantially equal to one-half the height and width of the rail ends, said rail ends being provided substantially midway the length of the rabbets and midway the height of the rail with a laterally extending opening defining channels in the 30 upper and lower surfaces respectively of the opposed tongues, and means adapted to be extended through the registering openings in the rail ends for preventing relative longitudinal shifting of those ends.
